UNITED STATES PATENT OFFICE.

HERMAN C. MOEN AND GEORGE H. BENSON, OF CAMBRIDGE, WISCONSIN.

CONVEYING APPARATUS.

1,415,892.

Specification of Letters Patent. Patented May 16, 1922.

Application filed April 5, 1921. Serial No. 458,762.

To all whom it may concern:

Be it known that we, HERMAN C. MOEN and GEORGE H. BENSON, citizens of the United States, residing at Cambridge, in the county of Dane and State of Wisconsin, have invented new and useful Improvements in Conveying Apparatus, of which the following is a specification.

The apparatus which is the subject matter of the present application for patent has been designed to facilitate the removal of manure and litter from barns, stables etc., and it consists of a receptacle which is removably seated in the usual gutter of the barn floor, and connected to an elevating and conveying apparatus, whereby said receptacle may be easily conveyed to the outside of the barn or other structure and dumped into a manure spreader, or piled up for future hauling.

In order that the invention may be better understood, reference is had to the accompanying drawing, forming a part of this specification, and in said drawing,

Figure 1 is a cross section of a fragment of a barn or similar structure, showing the application of the invention;

Fig. 2 is an elevation of the elevating and conveying apparatus;

Fig. 3 is an enlarged cross-section on the line 3—3 of Fig. 2, and,

Fig. 4 is a plan view of the receptacle.

Referring specifically to the drawing, 10 denotes the floor of a barn, stable or similar structure, provided with a gutter 11 to receive the manure, litter etc. As the removal of the contents of the gutter involves much work, there is provided a receptacle 12 which is removably seated in the gutter and connected to an elevating and conveying apparatus. This receptacle is made of sheet metal or other suitable material and it is dimensioned to extend throughout substantially the entire length of the gutter, so that the material does not enter the gutter but is discharged into the receptacle only, in view of which its disposal is readily effected, said receptacle being removably positioned in the gutter and connected to the elevating and conveying apparatus to be presently described. In view of the length of the receptacle, it is braced at intervals by cross angle irons 13. If the gutter is of such length as to make a single receptacle impractical, the receptacle may be made in sections.

At the ends of the receptacle 12 are trun-

nions 14 and 15, respectively, for connection of the receptacle with the elevating and conveying apparatus, and in order to close up or cover the space between the ends of the receptacle and the gutter ends occupied by the trunnions, the receptacle ends carry hinged cover plates 16 adapted to be swung over the gutter space when the receptacle is in place so that the material cannot collect in this space.

The elevating and conveying apparatus hereinbefore referred to comprises the following parts:

To the ceiling or rafters of the barn, or to any other suitable overhead support is attached a track 17 running the entire length of the gutter 11 and extending to the outside of the barn into the yard where the litter or manure is to be dumped, either onto a manure spreader, or a pile for future hauling.

On the track 17 is mounted for travel thereon, a carriage composed of two longitudinally spaced wheels 18 carrying a longitudinal beam 19 composed of a number of telescopically connected tubular sections which are locked together by set screws 20. The beam is therefore adjustable as to length according to the length of the receptacle 12. The wheels 18 are provided with suitable supporting frames 21 carrying depending hangers 22 which support the beam 19.

The ends of the beam 19 are downturned, 90 as shown at 23, and at the bottom said downturned ends carry bearings 24 in which is journaled a shaft 25 which serves as a drum on which are adapted to be wound two laterally spaced hoisting chains or lines 26 carrying means for attachment to the receptacle 12. The shaft or drum 25 is also composed of telescopically connected tubular sections locked in adjusted position by set screws 27, so that adjustment to conform to the length 95 of the beam 19 may be made.

One end of the shaft or drum 25 is provided with a crank handle 28 for operating the same to wind up and unwind the lines 26. The crank handle carries a locking pin 105 29 adapted to be inserted into a hole in the adjacent end portion 23 of the beam 19, and thus hold the shaft or drum from turning to allow the lines 26 to unwind when the receptacle 12 has been elevated to conveying 110 position.

The free ends of the chains 26 carry bear-

ing members 31 and 32, respectively, into which the trunnions 14 and 15 are adapted to be inserted for connection of the receptacle 12 with the elevating and conveying means. In order to prevent the receptacle from tilting and thus spilling the load while it is being elevated and conveyed to the dumping place, the bearing member 31 carries a pivoted latch lever 33 which is adapted 10 to be seated in a keeper recess 34 in the end of the trunnion 14. When the receptacle reaches the dumping place, the latch lever is swung out of the keeper recess, whereupon the trunnions are left free to turn in the bearing members, and the receptacle now turns over or rotates to dump its load.

We claim:

1. The combination with a receptacle; of a conveyer mounted for travel above the receptacle, and elevating means for the receptacle having a detachable connection therewith and supported by the conveyer, said elevating means including hoisting
- 20
- 15

lines, bearings carried by the free ends of said lines, the receptacle having trunnions 25 at its ends adapted to be removably seated in said bearings, one of the trunnions having a keeper recess, and a latch lever carried by one of the bearings and adapted to seat in said recess.

30 2. The combination with a receptacle; of an overhead track, a conveyer carriage composed of a pair of longitudinally spaced wheels, supporting frames for said wheels, and a beam supported by said frames, said beam being composed of sections which are adjustable as to length, a winding drum composed of sections which are adjustable as to length, bearings for said drum carried by the aforesaid beam, hoisting lines connected 40 to the drum, and means for detachably connecting said lines to the receptacle.

In testimony whereof we affix our signatures.

HERMAN C. MOEN.
GEO. H. BENSON.
